FIG.1

FIG.3

FIG.4

FIG. 2

FIG. 1 is a perspective view from a position to the front and right of and slightly above my dual access kitchen storage cabinet;

FIG. 2 is a perspective view of the front of my dual access kitchen storage cabinet, with the front access doors open and the dual access drawer withdrawn from the cabinet;

FIG. 3 is a rear elevation view of the cabinet;

FIG. 4 is a view in rear elevation of the cabinet of FIG. 1 but wherein the lower portion thereof is provided with paired door members rather than a plain unornamented surface as in FIG. 3.

I claim:

The ornamental design for the dual access kitchen storage cabinet, substantially as shown and described.
